UNITED STATES PATENT OFFICE.

GEORGE F. HOFFMAN, OF PHILADELPHIA, PENNSYLVANIA.

DESIGN FOR A HAMMOCK-STAND.

No. 39,975.

Specification for Design.

Patented May 4, 1909.

Application filed March 12, 1909. Serial No. 483,082. Term of patent 7 years.

To all whom it may concern:

Be it known that I, GEORGE F. HOFFMAN, a citizen of the United States, residing at Philadelphia, in the county of Philadelphia and State of Pennsylvania, have invented a new, original, and ornamental Design for a Hammock-Stand, of which the following is a specification, reference being had to the accompanying drawing, forming part thereof, in which there is illustrated in perspective a view of a hammock-stand, showing my new design.

I claim:

The ornamental design for a hammock stand as shown.

GEORGE F. HOFFMAN.
